DETECTOR CIRCUITS

Palmer Hunt Craig, Bethlehem, Pa., assignor to
Invex Corporation, New York, N. Y., a corpora-
tion of New York

Application February 28, 1935, Serial No. 8,741

11 Claims. (Cl. 177—352.2)

5 My invention relates to electric circuits for detecting the presence or proximity of conducting bodies. The circuits of my invention may be employed in burglar alarm systems, traffic counting systems, and in manufacturing processes where it is desired to detect the presence of a conducting body in a certain locality. One form of my invention may also be used for determining the weight of objects.

10 This application is in part a continuation of application Serial No. 688,249, filed September 5, 1933, Patent No. 2,001,838, and also contains subject matter disclosed in my copending applications Serial Nos. 577,691, Patent No. 2,001,836, filed 15 November 27, 1931, and 646,662, Patent No. 2,001,837, filed December 10, 1932.

Figures 1 to 3 of the accompanying drawing are diagrams of detector circuits taken from my application Serial No. 688,249;

20 Figures 4, 5, 6, 8 and 9 are diagrams of circuits taken from my application Serial No. 577,691; and

Figure 7 is a diagram of a circuit taken from my application 646,662.

25 My invention involves the use of a gaseous relay tube having an electron emitting cathode, an anode and a grid or control electrode. In one form of gaseous relay the control element is located within the envelope or tube in the space between the cathode and the anode, and in another form, the control or grid element is located outside of the envelope, usually at a point lying 30 being the cathode and the anode. I prefer to use the second form of gaseous relay, that is, the type with the external grid, but the internal grid type may be used, if desired.

35 Referring to Figure 1, relay tube 1 is formed of a glass bulb provided with an electron emitting cathode 2, an anode 3, and an external grid or control electrode 4. The tube 1 is also provided with a gaseous atmosphere such as mercury vapor neon, xenon, or other suitable ionizable gas or vapor. The relay tube may consist of a type 866 hot-cathode mercury vapor rectifier described in Q. S. T. for February, 1929, pages 20 to 22, and 40 provided with an external grid. Various forms of relay tubes are also illustrated in Electronics for March, 1933, pages 70 to 72. The cathode 2 is heated from a low voltage winding 5 of a transformer T, the primary winding of which is connected across the terminals of an alternating current source 6—7. A suitable alarm 16, or an indicating device 16a, is connected in a circuit across the terminals 6—7 in series with the 45 anode-cathode elements of the tube 1. One terminal of high voltage winding 9 of transformer T is connected to the cathode heating circuit by condenser 11, and the other terminal is connected to grid 4 by variable condenser 12. The polarity 50 of winding 9 is such that when the anode 3 is

positive with respect to the cathode 2, the grid 4 is negative with respect to the cathode. A variable resistance 17 may be included in the anode circuit, if desired, for limiting the anode current.

5 Since the potential impressed upon the grid 4 by the condenser 12 is opposite in phase to the anode potential, the grid 4 exerts a restraining influence upon the arc in the relay 1, and by varying the value of condenser 12, (or of condenser 11) the starting of the arc in the tube 10 may be controlled. It will be understood that increasing the value of the condenser increases the potential applied to the grid and thereby decreases the effective value of the anode current.

15 The circuit of Figure 1 is quite sensitive to capacity variations produced in the grid circuit by conducting bodies near the grid circuit, especially when the grid potential is adjusted to the critical value where the anode current is just prevented from starting. In order to make the circuit more 20 sensitive for detecting the presence of conducting bodies, a conducting grid or plate 18 is connected to the grid 4 and is arranged in the locality to be protected against burglars. When the condenser 12 is adjusted so that the arc within the 25 tube 1 is just prevented from forming, the approach of a person or any conducting body within the vicinity of the plate 18 will reduce the control potential applied to the grid 4 and permit the 30 arc to be established, thereby energizing the signal 16. It will be obvious that the condenser 11 may be omitted, and the lower terminal of winding 9 connected directly to the cathode circuit.

35 The arrangements described above may be employed for the purpose of detecting the passage of persons or objects along a passageway by placing the capacity plate 18 at a point along the passageway so that the body or object to be detected passes near the plate. The variation in the anode current caused by the passage of such persons or objects may be utilized through well known 40 means for indicating or recording the number of passages taking place, or for indicating the presence of an object at a certain point in the passageway. The indicating device may be located 45 at a point remote from the control tube. Furthermore, with the arrangement shown and with proper adjustment of condensers 11 and 12, it is possible by an indicating meter 16a to obtain an 50 indication of the nearness or proximity of the object with respect to the plate 18. However, for greatest sensitivity in detecting the presence of objects, the adjustment will be such that the operation of the tube is substantially on-and-off.

55 The arrangement of Figure 1 may be modified by omitting the plate 18 and by forming the variable condenser 12 of plates of suitable size arranged on opposite sides of a passageway as indicated in Figure 2. The condenser plates are indicated at 12a and 12b, and the object to be de- 60

ected is indicated at 19 between the plates. With this modification, the tube is normally inactive, but the passage of an object between the plates of the condenser causes the arc in the tube to 5 strike, and the resulting current operates the signal or recording device 16. It is obvious that instead of connecting the grid control circuit to a point on the cathode heating circuit, this circuit may be connected to the anode lead or to any 10 point on the anode-cathode circuit. This modified connection may be embodied in any of the detector circuits of this application, and is obtained in Figure 2 by the use of switch 22, but it will be understood that the connection may be 15 made directly to the anode without the use of the switch.

In the operation of Figure 2, the tube would be normally conducting, and the passage of the body or object 19 between the condenser plates will 20 cause an increase in the restraining potential applied to the grid and will reduce the effective 25 value of the anode current flowing in the circuit.

Figure 3 illustrates a third detector circuit somewhat like Figure 1. In this arrangement, 25 the condensers 11 and 12 are omitted, and a potentiometer comprising a resistance 10 and a variable contact 10a is employed for the purpose of adjusting the restraining potential applied to the grid. The action of this circuit is substantially like that of the circuit in Figure 1, except that more of a trigger-like action is obtained than in the circuit of Figure 1, due to the operation which results in the abrupt establishment and the cutting-off of the anode current for 30 slight variations below and above a critical value of the control voltage.

The arrangement shown in Figure 4 is taken from my copending application Serial No. 577,691, and also disclosed in my application Ser. No. 40 646,662. This circuit embodies features disclosed in both Figures 2 and 3, and corresponding elements are indicated by corresponding reference numerals. The condenser 8 connected in series 45 with resistance 10 is for the purpose of fixing the phase of the grid or control potential so that it lags the anode potential by an angle of the order of 135 degrees for the purpose of giving a more uniform control of the anode current by variation of the contact 10a as more fully disclosed in my copending application Serial No. 577,691. The operation of this circuit is like that of Figure 2, since the presence of the conducting body 19 between the plates of the grid condenser causes a decrease in the anode current and produces a corresponding operation of the indicating or recording device 16. As previously disclosed in my application Ser. No. 646,662, the grid circuit return may be connected to the anode circuit instead of the cathode circuit.

60 The circuit arrangement shown in Figure 5, previously disclosed in my application Serial No. 577,691 involves the use of an additional grid 4a on the tube 1. This circuit is somewhat like the circuit shown in Figure 4, except that the condenser 12 is connected between the second grid 4a and the cathode circuit. In the operation of this circuit, the potential applied to the grid 4 exerts a restraining influence upon the anode current, and the passage of a conducting body 19 65 between the plates of the condenser 12 reduces or impairs the restraining action of the grid 4 and causes a greater anode current to flow which is either recorded or indicated by the device 16.

The circuit shown in Figure 6 is like the circuit 70 of Figure 4 and differs therefrom in that the de-

tecting condenser 12 is connected between the grid 4 and the cathode circuit, and a small condenser 13 is inserted between the variable tap on resistance 10 and the grid 4. This condenser may be omitted if desired. This circuit operates 5 in substantially the same manner as Figures 1 and 3, except that due to the particular phase displacement between the control voltage and the anode voltage, a more uniform variation of the anode current is obtained than in Figures 10 1 and 3.

Figure 7 is a composite circuit diagram illustrating circuits originally disclosed in my application Ser. No. 646,662. This circuit differs from Figure 1 in that the phase determining elements 15 8 and 10 are connected across the secondary winding 9, and the capacity element 18a is shown as a short length of wire. The return for the grid circuit may be connected either to the cathode circuit or to the anode lead, and for the sake of 20 convenience, these two modifications have been illustrated by means of the switch 22. The wire 18 is arranged so that the object to be detected comes near the wire, and the presence of the object reduces the potential upon the grid and 25 causes an increase in the anode current.

Figure 8 is a modification of the circuit diagram shown in Figure 4. In this arrangement, the anode current for the tube is supplied from a secondary winding 9a instead of directly from 30 the alternating current terminal 6—7 as in Figure 4. It is obvious that an additional secondary winding corresponding to winding 9a may be provided on any of the remaining circuits illustrated in this application for supplying the anode current to the tube 1. It is apparent that the two secondary windings 9 and 9a are equivalent to 35 a single secondary winding with an intermediate tap connected to the cathode circuit, and a single tapped secondary may be employed, if desired. The operation of Figure 8 is the same as the operation of Figure 4.

In Figure 9, I have shown the circuit of Figure 4 applied to a system for indicating the weight of objects. In this arrangement, the condenser 12a—12b shown in Figure 4 takes the form of a 45 capacity scale 13 comprising a fixed plate 13a and a movable plate 13b suspended above the fixed plate by a spring 13c from a suitable support. The object 14 to be weighed is placed upon 50 movable plate 13, and depresses this plate to a greater or less extent toward plate 13a, and thereby changes the value of its capacity in accordance with the weight of the object. An electric meter M is inserted in the anode circuit with tube 1, and the scale of this meter may be graduated to indicate weight in pounds or any other desirable unit. The meter M may be located at 55 a point remote from the weighing scale 13. The movable plate 13b may be arranged below the 60 fixed plate 13a, and the calibration of the meter M changed accordingly. Figure 9 also includes a separate secondary winding 9a for supplying space current to the anode circuit as in Figure 8. It is apparent that condenser 8 in Figure 9, and 65 also in Figures 4, 5 and 6, may be included in the circuit at the upper end of secondary winding 9, if desired, as shown in Figure 8.

Any of the circuits shown in Figures 2, 4 to 6 and 8 may be employed for the purpose of detecting the passage of persons or objects along a passageway by forming the condenser plates 12a—12b of suitable size arranged on opposite 70 sides of the passageway. The passage of a person or an object, such as an automobile, between 75

the fixed plates will vary the capacity of the condenser and cause the anode current to vary correspondingly. The variation in anode current may be utilized through well known means for indicating or recording the number of passages taking place, or for indicating the presence of an object at a certain point in the passageway. The indicating device may be located at a point remote from the control tube. The circuits of Figures 1, 3 and 7 may also be used for the purpose indicated above, by arranging the capacity elements 18 or 18a adjacent the passageway.

The circuit arrangements shown in Figures 2, 4 to 6 and 8 may be employed for detecting changes in characteristics of various materials in manufacturing processes by passing the material between the condenser plates 12a—12b, and the resulting changes in capacity of the condenser are reflected in the output circuit. For example, the presence of small metal particles or foreign substances in chewing gum and candy may be detected by passing the gum or candy between the condenser plates in a thin layer and noting the changes in anode current. These circuits may also be employed for detecting breaks in the manufacture of paper by passing the paper between the condenser plates, and the change in the dielectric constant of the condenser produced by a break in the paper will produce a change in the anode current sufficient to operate a suitable signal. The circuits of Figures 1, 3 and 7 may also be employed for the purpose indicated above by passing the material between capacity elements 18 or 18a and a grounded plate or wire spaced from the capacity elements to form a condenser arrangement the capacity of which is varied by the material under test.

Figures 1 to 3 produce more of an on-and-off control than Figures 4 to 9, due to the fact that the control potential is 180 degrees out of phase with the anode potential. The circuits of Figures 4 to 9 may be adjusted so that the presence of an extraneous object merely changes the anode current from one value to another, or, in case external grids (or grids insulated from the space current discharge) are employed, it is possible, by adjusting the grid potential to a high value, to completely cut off the anode current, and at this point the tube is quite sensitive to small changes in grid voltage, only a small decrease in grid voltage being sufficient to allow an appreciable current to flow in the anode circuit. By adjusting the value of condenser 11 in Figure 2, or by adjusting the grid contact on resistance 10 in Figures 4 and 8, it is possible to operate these circuits so that the presence of the object 19 between the condenser plates 12a—12b merely reduces the anode current from one value to another, or the adjustment may be such as to cause the anode current to be completely cut off by the presence of object 19.

In Figures 1 to 3 the grid voltage is opposite in phase to the anode voltage, but in Figures 4 to 9 the grid voltage lags behind the anode voltage by an angle less than 180 degrees. The amount of lag depends upon the operation desired, but the circuits will operate with a lag varying from a few degrees to 180 degrees. I prefer, however, to operate between the range of 90 degrees and 180 degrees, since in this range a wider variation of anode current is obtained. It will also be noted that the phase relation between the grid and anode voltages remains fixed in all circuits of my invention, and the relay is controlled by variation in magnitude of the control voltages.

While I have illustrated by invention as employing a gaseous relay tube having a heated electron emitting cathode, it will be understood that gaseous relays having other types of cathodes may be employed, for example, I may use a gaseous relay of known type having a cold cathode and a keep-alive electrode for maintaining the gaseous atmosphere ionized. Also, instead of using a heated cathode of the type illustrated, the well known mercury pool cathode may be employed with a keep-alive circuit.

Many modifications can be made in the circuit arrangements disclosed herein without departing from my invention. For example, in Figures 1 and 2, and also Figures 4, 5, 6, 7 and 9, the condenser 11, or the condenser 8, may be omitted in case there is sufficient capacity existing between the winding 9 and the cathode winding 5 to serve the function of the omitted condenser. In this case the lower terminal of winding 9 will remain free and disconnected. Also, the phase determining condenser 8 in Figures 4 to 9 may be inserted in the primary circuit of the grid transformer instead of in the secondary circuit as shown, and a separate transformer may be employed for supplying heating current to the cathode.

In the appended claims, the term "lagging" is to be interpreted to cover any lagging phase from a few degrees to 180 degrees. Also, the term "signal device" is intended to cover audible and visual indicators as well as recording and counting devices. The term "thermionic valve" is to be interpreted broadly to cover any of the various types of gaseous relay described herein.

What I claim is:

1. Electrical apparatus comprising a source of alternating electric current, a transformer the primary of which is connected to said source and having two secondaries, a thermionic valve the filament of which is connected across one of said secondaries, connections from the other secondary to the grid and plate of said valve, a condenser in the connection between the second secondary and the grid of said valve, and means varying the capacity of said condenser and arranged to be actuated by an extraneous object.

2. Electrical apparatus comprising a source of alternating electric current, a transformer the primary of which is connected to said source and having two secondaries, a thermionic valve the filament of which is connected across one of said secondaries, connections from the other secondary to the grid and plate of said valve, a condenser in the connection between the second secondary and the grid of said valve, and means moving one of the plates of said condenser to vary the capacity of said condenser, said movement being controlled by an extraneous object.

3. A circuit comprising a source of alternating electrical energy, a transformer having a primary connected to said source, and two secondaries, a thermionic valve having its filament connected to one of said secondaries, a resistance element connected in parallel with a portion of the second secondary an adjustable connection from said resistance element including a variable condenser and connected to the grid of said valve, and a connection from one end of the second secondary to the plate of said valve including a device to be actuated by current passing through said connection.

4. A circuit comprising a source of alternating electrical energy, a transformer having a primary connected to said source and two secondaries, a

- thermionic valve having its filament connected to one of said secondaries, a resistance element connected in parallel with a portion of the second secondary, an adjustable connection from said 5 resistance element including a condenser and connected to the grid of said valve, a connection from one end of the second secondary to the plate of said valve including a device to be actuated by current passing through said connection, and 10 15 20 25 30 35 40 45 50 55 60 65 70 means for conducting current from the grid of said valve.
5. In combination, a source of alternating current, a gaseous relay device having a cathode an anode and a control electrode, a work circuit including said source and the space current path of said device, a signal device included in said work circuit, said gaseous relay having a characteristic such that plate current is cut off at a certain value of negative voltage on the control 10 15 20 25 30 35 40 45 50 55 60 65 70 electrode and the arc discharge is established at a lower negative control voltage, means for supplying to said control electrode an alternating voltage opposite in phase with respect to said anode and of sufficient magnitude to normally prevent current from flowing in said work circuit, and a capacity element connected to said control electrode and being operative upon the approach of a conducting body in proximity thereto to reduce the voltage applied to said control electrode to a value to establish a discharge in said relay and thereby effect energization of said signal device.
6. In an electric control system, the combination of a source of alternating current, a vapor electric device having a cathode and an anode enclosed within an insulating envelope, and a control electrode external of said envelope, a work circuit including said source and the space current path of said device, a signal device included in said work circuit, said gaseous relay having a characteristic such that plate current is cut off at a certain value of negative voltage on the control electrode and the arc discharge is established at a lower negative control voltage, means for supplying to said external control electrode an alternating voltage opposite in phase with respect to said anode and of sufficient magnitude to normally prevent current from flowing in said work circuit, and a capacity element connected to said control electrode and being operative upon the approach of a conducting body in proximity thereto to reduce the voltage applied to said control electrode to a value to establish a discharge in said relay and thereby effect energization of said signal device.
7. In combination, a source of alternating current, an arc discharge device having a cathode an anode and a control electrode, a work circuit including said source and the space current path of said device, a signal device included in said work circuit, said gaseous relay having a characteristic such that plate current is cut off at a certain value of negative voltage on the control electrode and the arc discharge is established at a lower negative control voltage, a transformer connected to said source and having a secondary winding for supplying to said control electrode an alternating voltage substantially opposite in phase with respect to said anode, means for adjusting the magnitude of the grid voltage to normally prevent current from flowing in said work circuit, and a capacity element connected to said control electrode and being operative upon the

approach of a conducting body in proximity thereto to reduce the voltage applied to said control electrode to a value to establish a discharge in said relay and thereby effect energization of said signal device.

8. In combination, a source of alternating current, a gaseous relay device having a cathode an anode and a control electrode, a work circuit including said source and the space current path of said device, a signal device included in said work circuit, said gaseous relay having a characteristic such that plate current is cut off at a certain value of negative voltage on the control electrode and the arc discharge is established at a lower negative control voltage, means for supplying to said control electrode an alternating voltage of fixed lagging phase with respect to the voltage of said anode, means for adjusting the amplitude of the control voltage, and a capacity element connected to said control electrode and being operative upon the approach of a conducting body in proximity thereto to change the amplitude of the voltage applied to said control electrode while maintaining the phase thereof substantially unchanged and thereby effect operation of said signal device.

9. In combination, a source of alternating current, a gaseous relay device having a cathode an anode and a control electrode, a work circuit including said source and the space current path of said device, a signal device included in said work circuit, means for supplying to said control electrode an alternating voltage lagging in phase with respect to the voltage of said anode, means for adjusting the amplitude of the control voltage, and a condenser connected between the control electrode and the cathode, said condenser being arranged to have its capacity varied by an extraneous object passing between its plates.

10. In combination, a source of alternating current, a gaseous relay device having a cathode an anode and a control electrode, a work circuit including said source and the space current path of said device, a signal device included in said work circuit, a condenser for connecting said control electrode to a source of alternating voltage lagging in phase with respect to the voltage of said anode, means for adjusting the amplitude of the voltage applied to said control electrode through said condenser, said condenser being arranged to have its capacity varied by an extraneous object passing between its plates.

11. In combination, a source of alternating current, a gaseous relay device having a cathode and an anode enclosed within an envelope and a control electrode located externally of the envelope, a work circuit including said source and the space current path of said relay, a signal device included in said work circuit, a transformer connected to said source and having a secondary winding, circuit connections from said secondary winding for supplying to said control electrode a control potential which is negative with respect to the anode potential, adjustable means in said connection for adjusting the value of said control potential to a point near the critical cut-off value, and a capacity element connected to said control electrode and being operative upon the approach of a conducting body in proximity thereto to vary the potential applied to said grid without reversing the phase thereof.

PALMER HUNT CRAIG.
